(57) **CLAIM**

The ornamental design for a sink trap collection device, as shown and described.

DESCRIPTION

FIG. 1 is an elevational perspective view of a sink trap collection device showing my new design;

FIG. 2 is a front side elevational view thereof;

FIG. 3 is a back side elevational view thereof;

FIG. 4 is a top plan view thereof;

FIG. 5 is a left side elevational view thereof, and a right side elevational view is a mirror image thereof;

FIG. 6 is a bottom side plan view thereof; and,

FIG. 7 is an exploded, perspective view thereof.

The broken line showing in FIG. 1 is included for the purpose of illustrating environmental structure and forms no part of the claimed design.
